UNITED STATES PATENT OFFICE.

OLIVER E. BECKER, OF OAK PARK, ILLINOIS.

BRUSH FOR ELECTRICAL MACHINERY.

1,282,027.

Specification of Letters Patent. Patented Oct. 22, 1918.

Application filed March 11, 1918. Serial No. 221,865.

To all whom it may concern:

Be it known that I, OLIVER E. BECKER, a citizen of the United States, residing at Oak Park, in the county of Cook and State of Illinois, have invented a certain new and useful Improvement in Brushes for Electrical Machinery, of which the following is a full, clear, concise, and exact description, reference being had to the accompanying drawings, forming a part of this specification.

My invention relates to brushes for electrical machinery.

The matter of maintaining electrical contact between a stationary terminal and a moving commutator or collecting ring, or the like, is one of the most difficult practical problems in the industry. Numerous forms of brushes have been devised. Some have found particular favor for special uses. The gauze brush has persisted from the earliest stages of the development of the electrical industry and is now perhaps the best fitted and the most widely used for low voltage purposes.

An outline of the advantages of the gauze brush and its relation to the other types of brushes is set out in Patent No. 1,228,484, to which I make reference.

I have observed that one of the difficulties encountered in using gauze brushes is the tendency to spread or fray.

Gauze brushes are generally made by winding a strip of wire gauze into a roll, on a mandrel, then removing the mandrel and rolling or pressing the roll of gauze into rectangular prismatic form. The rolling or pressing compresses the gauze and makes the texture close and compact; at the same time it preserves the springiness of the material to permit it to adapt itself to seating on the commutator or ring surface. The top of the brush is generally dipped into solder and thereby filled to preserve the form of the brush as well as to provide a solid part for attachment of the lead or leads.

The object of my invention is to provide means for preventing the spreading or fraying without destroying or seriously impairing the resiliency and springiness or ventilation of the brush.

I have carried out the invention in a number of different ways, some of which I shall set forth at length. In general these different methods all aim to secure a connection

of limited extent between the gauze of different layers in the brush. This connection may be made by causing adhesion between surface coatings on adjacent layers, by localized fillings of a cementitious material such as solder, by localized welds, by lacing wires, or by other means.

In order to acquaint more fully those skilled in the art with the nature of the invention, I shall now set out in detail one manner of practising the invention.

In the accompanying drawings which form a part of the present specification,

Figure 1 is a cross-sectional view of a brush constructed in accordance with my invention, whereby the limited connection between layers is secured by spot welding;

Fig. 2 is a similar view of a brush constructed in accordance with my invention by spot soldering;

Fig. 3 is an isometric view of a brush made of gauze, having a surface coating which is caused to adhere at localized points to secure connection between the different layers of gauze;

Fig. 4 is an isometric view of a sheet of gauze having localized coatings or fillings of lubricating metal such as tin or the like;

Fig. 5 is an isometric view of a brush formed of the gauze in Fig. 4, showing the adhesion caused between said localized coatings or fillings and the adjacent gauze;

Fig. 6 illustrates a method of providing a superficial filling of a few of the outer layers of gauze; and

Fig. 7 is an isometric view of a brush having rows or strips of local adhesions between the outer layers of gauze.

As the manner of forming gauze brushes from sheets of gauze is well understood and as the broad idea of forming a brush from gauze is not my invention, I do not consider that it is necessary to describe in detail the steps of first rolling the gauze on a mandrel, then withdrawing the mandrel and thereafter forming the roll of gauze into a prismatic block or brush. The particular manner of forming the sheet gauze into the prismatic brush is set forth in the patent to Gutmann, No. 599,781.

In Fig. 1 I have illustrated a brush made up of gauze in which a few of the outer layers are joined together by local spot welds as shown at 10. This spot welding is preferably done in an electrical welding ma-

chine, although a flame from a blow torch may be employed to secure the weld. Thus the outer layers of gauze are braced by the interconnection, so that there is far less tendency for the sides of the brush to bulge out and bind in the holder, as has previously been the case. At the same time, the springiness or resiliency and the ventilating ability of the brush as a whole is not materially impaired and the brush is able to adapt itself to the surface of the commutator.

In Fig. 2 I have illustrated a brush made up of a plurality of sections 11, which are inclosed by a common wrapping of a sheet 15 or strip of gauze, binding the sections together. In this case the wrapper 12 and the sections 11 are joined together by local fillings of tin solder or the like 13, which may be applied in any preferred manner to join 20 the wrapping 12 with the material of the sections 11. It is to be understood that welding as disclosed in connection with Fig. 1, may be employed to fasten the sections and the wrapper together, or that the brush 25 of Fig. 1 might be made up of sections but connected by spot welds.

In Fig. 3 I have illustrated a brush formed of gauze having a lubricating coating as set out in Patent No. 1,228,484. The lubricating coating may be applied either before or after forming the gauze into the brush as is set out in that patent. When the brush has been formed with the lubricating coating I provide a series of localized connections by 30 applying pressure and heat at the various points to form a union between the lubricating coating of different layers, as shown at 14 in Fig. 3. This may be secured by applying heat electrically, by applying a hot 35 iron, or an open flame, or in any preferred manner. The essential idea is to secure a limited connection between layers, so that the tendency to spread or fray will be very largely counteracted without impairing the 40 resiliency and springiness of the brush.

In Figs. 4 and 5 I have illustrated the manner of making up a brush of this character by providing localized fillings of tin, lubricating metal or the like, at 15, in the 45 gauze sheet 16, prior to forming the same into the block or brush 17. In this event the gauze, after it is rolled into the block or brush form, is subjected to pressure and heat to cause the fillings 15 to adhere to adjacent layers of gauze so as to secure union 50 between layers. While I term the localized applications of tin as shown at 15 in Figs. 4 and 5 as fillings, it is to be understood that the meshes of the gauze need not actually be 55 filled, but that any quantity of tin or other uniting metal in quantity sufficient to form a union between adjacent layers is considered to come within the term "filling."

In Fig. 6 I have illustrated the manner 60 in which the outer layers of the gauze of the

brush may be united by solder or the like by first applying a flux to the outer layers and then uniting these layers by solder.

In carrying out this particular embodiment of the process I provide a hot metallic 70 plate as shown at 16, which has a thin film of melted tin or solder 17 thereupon. After the flux is applied to the outer layers of gauze on the brush, the brush is pressed against the plate 16 whereby the thin film 75 of tin or solder 17 permeates the outer layers of the brush to a limited extent, causing union between these layers as indicated at 18 in Fig. 6.

I have found that with the above method 80 the point at which the tin or solder is made to adhere, may be controlled by the application of the flux. Thus, as shown in Fig. 7, I may apply the flux only in strips as shown to secure localized fillings 19 in the form of 85 longitudinal strips in the outer layers of the brush. It is apparent that local spot fillings may be secured in the same manner by localizing the application of the flux and thus controlling the point at which the tin or 90 solder adheres.

Whether the local adhesions be caused by welding or soldering the effect is the same, namely a fixed molecular union between the adjacent parts.

I do not intend to be limited to the details shown and described, but intend to convey the essential and novel idea of forming limited union between different layers of the gauze brush in order to hold the sides 95 against bowing out and against fraying, without materially destroying or impairing the resiliency or ventilation of the brush. This idea is not to be confused with filling the end of the brush with solder, as 100 that has no bearing on my invention and it is never intended that the end of the brush which is filled with solder is to form actual contact with the commutator. A gauze brush which would be completely filled with 105 solder would not be different from a solid metal brush and would be subject to all the difficulties attendant upon the use of the solid metal brush.

I claim:

1. A gauze brush formed of layers of metallic gauze, having localized connecting means engaging only a limited number of the outer layers of the gauze for holding the outer layers of gauze against spreading. 115

2. A gauze brush of oblong cross section, having means providing localized areas of adhesion between adjacent layers of a part of the brush only at the wider sides of the brush.

3. A brush of the class described, comprising layers of gauze, the outer layers only of which are caused to adhere to each other rigidly in localized areas.

4. A brush of the class described, com- 130

prising layers of gauze, having cementing means for holding the outer layers of gauze against spreading or fraying, said means being formed of material of substantially the same or of a lower degree of hardness than the gauze of the brush.

5. The method of causing adhesion between the outer layers of a gauze brush, which consists in applying a cleansing compound to the areas which it is desired to cause to adhere, then heating the areas to the point of fusing the adjacent metallic surfaces.

6. The method of treating gauze brushes 15 to prevent bowing or spreading which consists in applying a fusible metal to the surfaces of the gauze to be united and locally applying heat to cause a union between parts of the gauze adjacent to the surface of the brush.

7. The method of treating gauze brushes to prevent bowing of the outer layers, which consists in applying a cementitious material for forming local adhesions only between 25 the outer parts of the gauze of the brush.

8. The methods of treating gauze brushes to prevent bowing of the outer layers,

which consists in forming local adhesions only between parts of the gauze of the brush, said local adhesions including parts 30 of the outer layers of the brush.

9. The method of treating gauze brushes to prevent bowing or spreading of the outer layers, which consists in providing fillings of tin or the like for parts of the brush only, 35 whereby the natural resiliency and ventilation of the brush is not materially impaired.

10. The method of treating gauze brushes to prevent bowing or spreading of the outer layers, which consists in locally cementing 40 the outer layers of gauze at a plurality of points to the layers beneath.

11. A gauze brush having front and back faces and means along the entire front and back faces for causing localized adhesions 45 between the outer layers of the gauze to prevent spreading or fraying of the gauze.

12. A gauze brush having local areas only of adhesion between a part of the layers only.

In witness whereof I hereunto subscribe my name this 5th day of March, A. D., 1918.

OLIVER E. BECKER.
